UNITED STATES PATENT OFFICE

FRANK J. KAUFMANN, OF TRIBES HILLS, NEW YORK

SEWING MACHINE

Application filed December 14, 1928. Serial No. 326,070.

This invention relates generally to sewing machines, particularly of the type known as "pop-stitch" machines, that is: a machine that simulates the ordinary over and under hand stitch.

The main object and feature of the invention is to produce a machine that will meet the very exacting requirements in glove making as to uniformity in appearance of a row of stitches and as to durability of such stitches. By this statement it is not intended to imply that the machine finds its usefulness exclusively in the stitching or sewing of gloves—it is merely intended to convey the fact that the machine is particularly applicable to this field. Obviously the machine can be used for many other purposes.

In the accompanying drawings the invention is disclosed in several concrete and preferred forms in which:

Fig. 1 is a front elevation, partly in section and with parts omitted, of a machine embodying one form of the invention. This view is complementary to Fig. 18.

Fig. 2 is an end elevation looking in the direction of arrow 2 of Fig. 1.

Fig. 3 is a top plan view of Fig. 1.

Fig. 4 is an end elevation looking in the direction of arrow 4 of Fig. 1.

Fig. 5 is a vertical sectional view substantially on the plane of line 5—5 of Fig. 1.

Fig. 6 is a horizontal sectional view substantially on the plane of line 6—6 of Fig. 1.

Figs. 7, 8 and 9 are views similar to Fig. 6 showing different positions which the parts will occupy during a cycle of the machine.

Fig. 10 is a vertical sectional view substantially on the plane of line 10—10 of Fig. 6.

Fig. 11 is a vertical sectional view substantially on the plane of line 11—11 of Fig. 6.

Figs. 12 and 13 are diagrammatic views in perspective of the manipulation of the thread during the slack take-up and tensioning steps.

Figs. 14 and 15 are enlarged sectional views through the material showing the

stitching before and after the tension has been applied to the stitch.

Fig. 16 is an enlarged sectional detail view of the upper needle chuck of the machine substantially on the plane of line 16—16 of Fig. 3.

Fig. 17 is a bottom plan view of Fig. 16.

Fig. 18 is a fragmentary front elevation, partly in section, of the material feeding mechanism. This view is complementary to Fig. 1.

Fig. 19 is a vertical sectional view on the plane of line 19—19 of Fig. 18.

Fig. 20 is an end elevation, looking in the direction of arrow 20 of Fig. 18, partly in section.

Fig. 21 is a detail view, partly in section, of the feed dog and its lifter cam.

Fig. 22 is a sectional view on the plane of line 22—22 of Fig. 21.

Fig. 23 is a fragmentary top plan view showing a modified form of the invention consisting of a coupling between the take-up devices.

Fig. 24 is a sectional view on the plane of line 24—24 of Fig. 23.

Fig. 25 is a fragmentary detail view of an antifriction means for the take-up devices.

Fig. 26 is a view similar to Fig. 6 illustrating a modified form of the invention.

Fig. 27 is a view in front elevation of a thread-clamping device which may be employed in the machine.

Fig. 28 is a sectional view on the plane of line 28—28 of Fig. 27.

Fig. 29 is a sectional view on the plane of line 29—29 of Fig. 28.

Fig. 30 is a plan view, partly in section, of one of the thread-clamping jaws.

Fig. 31 is a view similar to Fig. 6 showing a modified form of the invention of both Figs. 6 and 26.

Fig. 32 is a view similar to Fig. 8 but showing the construction disclosed in Fig. 31.

Figs. 33 and 34 are fragmentary views showing modifications of the form of the invention disclosed in Figs. 31 and 32.

The inherent difficulty with sewing machines of the type under consideration re-

sides in the fact that the sewing is carried on with a relatively short length of thread that diminishes in length with each cycle of the machine, and from this flows an especial 5 obstacle in forming successive stitches under uniform tension. When I speak here of tension I am referring not to the taking-up of the slack but to the pull exerted on the thread after the slack has been taken 10 up. This distinction will be readily apprehended by a consideration of Figs. 14 and 15 where 1 and 2 indicate two layers of material stitched together by means of thread 3. In Fig. 14 every stitch, except the last 15 one 4, has been placed under suitable and substantially uniform tension; stitch 4 has merely had its slack taken up. In Fig. 15 stitch 4 has been placed under suitable tension. Before proceeding to a detailed consideration of the means whereby suitable 20 and uniform tension is applied to a succession of stitches it may be well to describe the general organization of the machine, which machine involves a number of inventive 25 features.

The machine is characterized by the use of a double-pointed needle 5 having a centrally disposed eye 6 that receives thread 3, which thread is doubled back upon itself and 30 has its free ends tied together with a knot 7. 8 and 9 (Fig. 1) represent an upper and a lower needle chuck the needle passing through the material to be sewn and alternately held first by one and then by another 35 of said chucks. Each chuck is carried by a spindle 10 that reciprocates in suitable guides as 11 carried by the framework or upper and lower sewing heads 12. Suitable means are provided for reciprocating spindles 10, and thereby the chucks, said means, 40 in the present instance, taking the following form. 13 indicates a lever, pivoted at 14 and actuated by cam 15 (Fig. 5) by means of cam-actuated member 16. At its other 45 end, lever 13 is connected by means of link 17 (Fig. 1) to collar 18 fast on spindle 10. The train of connections just described are in duplicate, one train being for the upper and the other for the lower needle chuck 50 and the construction is exactly the same; the timing of the two trains of connections is, however, reversed one with respect to the other, as will be understood, so that the needle will pass from one chuck to the other 55 in proper sequence. The needle chucks may be constructed in many different ways, but a preferred construction (Figs. 16 and 17) is as follows: 19 are two chuck members forming a grasping means for the needle, and 60 these chuck members are carried by a cam sleeve 20 in threaded engagement at 21 with spindle 10. It will be apparent that rotation in one direction will raise the sleeve and bring the chuck members closer together 65 and that rotation in the other direction will

lower the sleeve and thereby admit of the chuck members being moved apart. Any suitable means may be utilized to open and close the chucks but, in this instance, cam sleeve 20 is provided with two wings 22 that 70 are acted upon by members 23 (Figs. 1, 3 and 4) pivoted at 24 and held in non-active position by spring 25. 26 indicates a rotatable member having dogs 27 to yieldingly engage members 23. It will be understood 75 that there are two members 23 associated with each chuck, one to act against each wing 22, and one to open and the other to close the chucks. To this end rotatable member 26 carries two dogs 27 circumferentially offset with respect to each other so as to alternately open and close a chuck. It will also be understood that the timing of the parts with respect to the upper and lower chucks is such that when the upper 80 chuck has closed on the needle the lower chuck will release it and vice versa. Rotatory motion can be imparted to members 26 in many ways but preferably they are mounted on shafts 28 each carrying a pinion 85 29 meshing with a gear 30 on cam shaft 31 or 32.

Intermediate the upper and lower chucks is a sewing table 33 on which the material to be sewn is placed, and adjacent this sewing table and intermediate the upper and lower sewing heads are the take-up devices 34 and 35. It will be seen from Fig. 1, and from the description so far given, that the arrangement of the parts forms a very compact and, notwithstanding this, an accessible construction. Inasmuch as the two take-up devices are constructed alike and differ merely in their timing, it will be sufficient to describe only one of them.

Cam shafts 31 and 32 are geared together by means of gears 36 and 37 and meshing with these gears are pinions 38 and 39 on shafts 40 and 41. Shaft 40 happens to be the power shaft but it will be obvious that power can be applied at any point to this train of connections. 42 and 43 are upright shafts mounted in the sewing heads and having here abutting engagement (Fig. 10) in the sewing table but are independently 100 rotatable. Suitable means to drive shafts 42 and 43 at certain stated intervals are here constructed as follows: 44 indicates a bevel gear on (say) shaft 42 meshing with a corresponding bevel gear 45 on horizontal shaft 110 46. Between shafts 40 and 46 (or 41 and 46) is a clutch device 47 which, when thrown in, causes rotation of shaft 42 (or 43). The clutch is controlled from cam 48 that engages cam roll 49 (Fig. 4) on lever 50 pivoted at 51, said lever being normally held in engagement with cam 48 by means of a spring 52. The upper end of lever 50 engages bifurcated end 53 of bell crank 54 pivoted at 55 and having a pin 56 engaged in 115 120 125 130

slotted clutch arm 57 pivoted at 58. Clutch arm 57 engages in a groove 59 of movable member of clutch 47. Spring 60 tends to close the clutch and cam 48 is utilized to open it, and that is really the only significance of the train of connections described. To stop shaft 46 exactly at the end of one revolution, said shaft may be provided with a notched disk 46^a into which one end of arm 54 enters when clutch 47 is thrown out. The upshot of the matter is that shaft 42 (or 43) is rotated at certain intervals in harmony with the other parts of the machine. Mounted on shaft 42 (or 43) is a cam 61 which I shall call a slack take-up and tension cam. 62 is a member or reel surrounding a concentric portion of cam 61 and mounted to rotate freely, and 63 is a take-up member or arm pivoted at 64 on the reel and provided with a cam engaging portion 65. A spring 66, the tension of which can be adjusted by threaded stem 67 in bracket 68, keeps portion 65 in engagement with cam 61. 69 is a stop to prevent undue movement of arm 63. Said arm 63 is provided with an extensible portion 70, slidingly mounted in said arm and provided with a loop engaging finger 71. 72 is a spring having one end anchored on the reel and the other on portion 70, said spring tending to urge portion 70 into a retracted position. Pivoted at 73 on the reel is a cam lever 74 having cam roll 75 and a slotted portion 76 engaging pin 77 of extensible portion 70. 78 is what I shall call an orbit-directing cam, relatively stationary with respect to the turning movement of the reel but adjustable in a manner presently to be described. When the needle has been passed through the material and transferred to the upper needle chuck (we will say) then clutch 47 is thrown in and shaft 42 begins to rotate carrying with it cam 61 which by its engagement with 65 causes rotation of the upper reel, the parts being now in the position shown in Figs. 3 and 6. As the reel rotates, cam roll 75 will engage cam 78 and will cause portion 70 to be projected outwardly against the tension of spring 72. This will cause finger 71 to travel in an orbit that intersects the plane of the needle or the loop of the thread (Fig. 7). Continuing its movement, the reel will now carry cam roll 75 past the high point of cam 78 and member 70 will therefore be retracted by spring 72. By referring to Fig. 12 it will be seen that during this period member 70 is pulling the slack thread through the material, the other end of the thread being looped over finger 71 of member 70^a of the lower reel which is not being driven by shaft 43 at this time and thereby causing the latter to rotate idly in a direction opposite to that of the upper reel. This continues until the lower loop of thread is freed from 70^a and all the slack thread has been drawn through the material. It will be evident that a point will eventually be reached where the thread will offer sufficient resistance to the advance of the upper reel and member 70 to cause compression of spring 66 thereby causing member 63 to swing around pivot 64 and thereby causing 65 to travel up surface 79 of cam 61 (see Fig. 8). The rise of surface 79 and the tension of spring 66 therefore determines in each instance the amount of tension that the thread is placed under after the slack has been taken up and it will be obvious that the amount of tension to which each stitch is subjected will be uniform. The length of time during which clutch 47 remains in is determined by the initial free length of the thread used and cannot exceed one revolution of shaft 42 and cam 61. It will be seen, however, that as the free ends of the thread diminish in length, the predetermined period during which the tension is applied occurs earlier and yet earlier in the cycle of operations, but that the duration of said period remain constant and that the amount of tension applied also remains constant or uniform. The result therefore is that 65 will disengage 79 earlier and earlier as the operation proceeds, but shaft 42 and cam 61 will always complete a revolution (when clutch 47 is thrown out) and will come to rest at the same point each time ready for the next cycle. Or to put this matter in different language: the two oscillatory take-up devices are opposed to each other and act in alternation, and each take-up device has intermittent periods of activity of diminishing duration as the sewing progresses, but this intermittent period is divided into a slack take-up period that diminishes after each alternation or as the length of the thread diminishes, but, on the other hand, the stitch tensioning period remains constant regardless of the length of the thread. Analyzing the mechanics of the situation, it is clear that shaft 42 (or 43) is a driving member, reel 62 a driven member and cam 61 and member 65 constitute a releasable driving connection between members 42 and 34 and that the stitch tensioning period coincides with the release period of 61 and 65. When now finger 71 of member 70^a of the lower reel takes hold of the thread, after the next stitch has been made, the upper reel will be pulled back or rotated reversely, under the influence of the pull of the thread, until said reel again occupies its original position with 79 against 65 ready for the next cycle. During the return movement of the upper reel, cam roll 75 will again pass through cam 78, but, as it is not now desired to have finger 71 travel in an orbit that passes through the plane of the needle, said cam 78 is shifted so as to make cam roll 75 reach the high point 80 earlier 130

and the orbit of member 70 and finger 71 will therefore be as indicated in Fig. 9. Any suitable means may be employed to shift cam 78 but in the present instance they are as follows: cam 78 is carried by a ring 81 surrounding a concentric portion of cam 61; and connected to ring 81 is an arm 82 pivotally connected at 83 to bell crank 84. Said bell crank 84 is pivotally supported at 85 and carries a cam-engaging member 86 to engage in cam 87 on shaft 31. The timing of cam 87 is such that when the reel is rotating idly on the return movement cam 78 will be in the position shown in Fig. 9, and, when the reel is moving under compulsion of shaft 42 and cam 61, cam 78 will be in the position shown in Figs. 3, 6, 7 and 8. A suitable brake mechanism, for the reel, is employed, and this brake mechanism may conveniently be operated by cam 87 because the timing of the brake mechanism can be the same as the timing of the shifting of cam 78. Accordingly, 88 indicates a brake member, here in the form of a roll carried by arm 89 pivotally supported at 90 on arm 84, and it will be seen that when arm 84 is moved by cam 87, to shift ring 81, brake member 88 will be moved toward or away from the periphery of the reel depending upon the direction of the movement of arm 84. The parts are so arranged that, when the reel is being moved by shaft 42, the brake member is in engagement with the periphery of the reel, so that, when shaft 42 ceases to drive the reel, the latter will immediately be brought to a state of rest, and, when the reel is rotating idly in a reverse direction, the brake member is not applied to the said periphery. 91 indicates a spring urging the brake member toward the reel and 92 is a stop to limit the motion of said brake member. It will be understood that, while I have described in detail only the construction of the parts associated with the upper reel and take-up device, there is a complementary arrangement of parts associated with the lower reel and the same reference characters will describe the lower construction, always bearing in mind, of course, that the lower reel and take-up device operate in alternation with the upper one and that therefore, as shown by the drawings, the timing of the lower parts is the reverse of the timing of the upper parts.

55 Suitable means are provided to feed the material during the sewing operation, and, in the present case, these means take the following form: referring to Figs. 18 to 22, 93 indicates a cam mounted on cam shaft 32, which cam, by means of lever 94, link 95 and lever 96 controls the movement of the movable member of clutch 97. Clutch 97 is interposed in the shaft connection 98 that derives its motion from gear 37 by means of pinion 99 and the arrangement is such that, whenever lever 94 passes over the high spots of cam 93, clutch 97 is thrown in and shaft 98 is rotated. Shaft 98 carries a gear 100 that meshes with intermediate pinions 101 which in turn drives pinion 102. Pinion 102 drives eccentric rollers 103 one of which engages in slot 104 and the other of which engages in slot 104^a of feed dog 105, which latter has a slotted end 106 that is supported by pin 107 on the framework. By the foregoing means the material is advanced one step after each passage of the needle through the material, feed finger 108 engaging the material and, in conjunction with the usual presser foot 109, effecting proper movement thereof.

10 The general operation of the machine is as follows: When the sewing operation is begun we will assume that the needle is in upper needle chuck 8. The needle is threaded, the thread is doubled back upon itself, the free ends thereof are tied together by a knot 7 (Fig. 14) and the thread is left hanging in sewing table 33. Upper needle chuck 8 now descends, passing the needle through the material and placing it within grasping range of lower needle chuck 9, which latter at this time is in a position close to the under side of sewing table 33. Lower chuck 9 now grasps the needle and upper chuck 8 releases it. The lower chuck begins its downward movement thereby carrying the thread through the material. Lower take-up device 35 now comes into action by throwing in lower clutch 47 and finger 71 of arm 70^a engages the double thread and draws a loop (four strands) and takes up the slack. This action continues until the entire length of thread has been pulled through the material when the resistance of the thread causes member 65 to ride up inclined surface 79 of cam 61 thereby applying the required tension to the stitch. During rotation of take-up device 35 brake 88 has been applied to the periphery thereof so that when the reel stops rotating there will be no rebound. Cam 61 completes its rotation and lower needle clutch 47 is thrown out. The goods or material is now fed forward one step by feed finger 108. Lower chuck 9 now begins to rise, carrying the needle with it and passing it through the material. The needle is now grasped by upper needle chuck 8 and released by lower needle chuck 9. Upper needle chuck 8 now begins to rise and upper take-up device 34 begins to rotate by reason of upper clutch 47 being thrown in, and finger 71 of arm 70 engages the thread. Meanwhile brake 88 of lower take-up device 35 has been released so that said lower take-up device is free to rotate backwardly under the pull of the thread, and cam 78 has been shifted so as to deflect finger 71 of arm 70^a out of the plane of the needle. The pulling

action of upper take-up device 34 continues until the lower take-up device releases the thread after which the required tension is applied to the stitch. The material is now fed forward another step by finger 108. The sewing operation now continues, the thread becoming shorter with each stitch, until the length of thread has been used up.

Some incidental features remain to be described. If desired the upper and lower reels may be coupled together as shown in Figs. 23 and 24 where 110 and 111 indicate two friction disks that respectively engage the upper and lower reels. Said disks are rotatably mounted in pivotally supported arms 112 and 113. Disk 110 carries a gear 114 and disk 111 carries a similar gear 115, said gears being held in mesh with each other by spring 116. It will now be seen that rotation of either of the reels in a certain direction will impart an equal movement to the other reel in the opposite direction, although the construction, as shown, admits of slippage so as to prevent jamming of the parts. The remainder of the construction involving shafts 42 and 43 as well as cams 61 etc. remains the same.

In Fig. 25 is shown a means to reduce friction on the thread, said means consisting of an anti-friction roller or glass pin 117 that may be employed in place of mere projections like 118.

In Fig. 26 is shown a means to cushion or relieve undue strain on the thread that may be caused by cam roll 75 in passing over the high point 80 of cam 78, such means consisting in anchoring one end of spring 72 on bell crank 119 pivoted at 120 on bracket 121 and having a cam roll 122 that engages in cam 123 on shaft 42 (or 43) which has a low spot 124 that corresponds to high spot 80 so that the parts may yield. A spring 125 is associated with 119 to oppose the action of roll 122 with respect to the low spot 124.

It is advantageous to relieve the needle of the side thrust of the thread, especially when applying the required tension to the stitch. For this reason there may be employed an abutment 126 (see especially Figs. 12 and 13) around which the thread passes and which thus, rather than the needle, receives the strain. But, if desired, a more positive device may be employed. Such a device is shown in Figs. 27 to 30. 127 and 128 indicate two complementary thread clamping jaws mounted on a carrier 129 that is pivotally supported at 130 on pivot 24 and which has an arm 131 that is acted upon by a cam 132 conveniently carried by shaft 28. A spring 133 keeps 131 in engagement with the cam. 127 is here a stationary jaw and 128 a movable jaw, the latter being pivoted to the former at 134 and a spring 135 tends to urge the jaws into their

closed position. Movable jaw 128 carries a cam surface 136 adapted to be engaged by actuator 137 which is a rod slidingly mounted on carrier 129 and normally held in an upper position by spring 138. A cam 139, also conveniently carried by shaft 28, actuates a bell crank 140 that engages the top of rod 137 to depress the same, at certain intervals, to thereby open movable jaw 128. It will be noted that carrier 129 and bell crank 140 are pivoted on the same center (24) and a spring 141 keeps 140 in engagement with cam 139. At appropriate times (when one or the other of the take-up devices is active) carrier 129 swings into position with respect to the needle and thread and the jaws are closed to clamp the thread and to thereby assume the strain so that none of it will fall on the needle. The conformation of the faces of the clamping jaws will be such as will be effective to do the work. In the present case they are triangular as seen best in Fig. 27.

In Figs. 31 and 32 is shown a further modification of the take-up device. Refer for a moment to Fig. 8 where it will be seen that, after the slack thread has been taken up, tension is imparted to the stitch during the period that 65 passes up incline 79, and also that during this period spring 66 becomes compressed or has its tension very materially increased. It is advantageous not to have the thread subjected to too great tension, and for this reason the device shown in Figs. 31 and 32 has been produced. It will be seen that spring 66^a instead of being anchored at a fixed point (as in Fig. 8 or Fig. 26) is carried by lever 150 which latter is pivoted at 151 on arm 63. 152 indicates an abutment, extraneously of arm 70 and lever 150, with which engages surface 153 of lever 150. It will now be evident that surface 153 can be an arc of a circle the center of which is pivot 64 and that, theoretically, there need be no additional compression of spring 66^a when the thread moves arm 63 on pivot 64 against the tension of spring 66^a. Surface 153 may be adjustable as by being pivoted at 154 and by being provided with a ratchet-and-pawl device 155, and it will be understood that by the tilting of surface 153 out of its concentric position the tension of spring 66^a can be either increased or decreased when arm 63 swings around pivot 64 due to resistance of the thread and the coaction of 65 and 79. In Figs. 31 and 32, the features of Fig. 26 happen to be included but it will be evident that the invention is in no wise dependent on the construction of Fig. 26. As a matter of fact, the means shown in Figs. 31 and 32 are susceptible of use in machines other than sewing machines and constitute an independent invention that may be embodied in widely different forms.

In Fig. 33, surface 153^a is straight instead of curved, and with this construction a slight compression of spring 66^a takes place when lever 63 turns on pivot 64 in response to the resistance of the thread.

5 In Fig. 34 there is a reversal of the parts. Instead of surface 153 being on lever 150, abutment 152^a constitutes a surface that may be adjusted as shown to obtain different 10 effects, and lever 150 carries a roller 154^a to engage surface 152^a.

It will be evident that the tension of spring 66^a may be initially adjusted by threaded stem 67^a, and that thereafter said 15 tension may be controlled by the compensating anchorage described.

I claim:

1. A sewing machine including: two needle chucks to alternately receive a needle 20 that travels back and forth between them to form pop-stitches from a constantly diminishing length of thread, two opposed loop-engaging take-up devices, acting in alternation in opposite directions one to pay 25 out the thread and the other to take up the slack thread and to tension the stitch, having intermittent periods of activity of diminishing duration, each intermittent period being in a given direction and being divided into 30 a slack take-up period that diminishes after each alternation and a stitch tensioning period that remains constant, driving means to move each take-up device, during its period of activity, in a given direction in a 35 path that intersects the plane of the needle to thereby engage the thread loop and thereafter, in the same direction, while taking up the slack and tensioning the stitch, and means to thereafter disengage the driving 40 means from the take-up device to which it is connected, said take-up device, during its return movement in the opposite direction, retaining the loop under tension while paying out the thread.

45 2. A sewing machine including: two needle chucks to alternately receive a needle that travels back and forth between them to form pop-stitches from a constantly diminishing length of thread, two opposed 50 loop-engaging take-up devices, acting in alternation in opposite directions one to pay out the thread and the other to take up the slack thread and to tension the stitch, having 55 intermittent periods of activity of diminishing duration, each intermittent period being in a given direction and being divided into a slack take-up period that diminishes after each alternation and a stitch tensioning period that remains constant, driving 60 means to move each take-up device, during its period of activity, in a given direction in a path that intersects the plane of the needle to thereby engage the thread loop and thereafter, in the same direction, while taking up 65 the slack and tensioning the stitch, means to 70 thereafter disengage the driving means from the take-up device to which it is connected, said take-up device, during its return movement in the opposite direction.

75 thereafter disengage the driving means from the take-up device to which it is connected, said take-up device, during its return movement in the opposite direction, retaining the loop under tension while paying out the 70 thread, means, including rocking members, to reciprocate the chucks, rotating members to open and close the needle chucks, and intermittently rotatable members having periods of activity of constant duration to 75 actuate the take-up devices.

80 3. A sewing machine including: two needle chucks to alternately receive a needle that travels back and forth between them to form pop-stitches from a constantly diminishing length of thread, two opposed 85 loop-engaging take-up devices, acting in alternation in opposite directions, one to pay out the thread and the other to take up the slack thread and to tension the stitch, having intermittent periods of activity of diminishing 90 duration, each intermittent period being in a given direction and being divided into a slack take-up period that diminishes after each alternation and a stitch tensioning 95 period that remains constant, driving means to move each take-up device, during its period of activity, in a given direction in a path that intersects the plane of the needle to thereby engage the thread loop and thereafter, in the same direction, while taking up the slack and tensioning the stitch, means to 100 thereafter disengage the driving means from the take-up device to which it is connected, said take-up device, during its return movement in the opposite direction, retaining the loop under tension while paying out the thread, and intermittently rotatable members having periods of activity of constant 105 duration to actuate the take-up devices.

110 4. A sewing machine including: two needle chucks to alternately receive a needle that travels back and forth between them to form pop-stitches from a constantly diminishing length of thread, two opposed 115 loop-engaging take-up devices, acting in alternation in opposite directions one to pay out the thread and the other to take up the slack thread and to tension the stitch, having intermittent periods of activity of diminishing 120 duration, each intermittent period being in a given direction and being divided into a slack take-up period that diminishes after each alternation and a stitch tensioning period that remains constant, driving means to move each take-up device, during its period of activity, in a given direction in a path that intersects the plane of the needle to thereby engage the thread loop and thereafter, in the same direction, while taking up the slack and tensioning the stitch, means to 125 thereafter disengage the driving means from the take-up device to which it is connected, said take-up device, during its return movement in the opposite direction.

tion, retaining the loop under tension while paying out the thread, and intermittently rotatable members each making a single revolution to each cycle of the machine to 5 actuate the take-up devices.

5. In a sewing machine, a thread take-up device, to act a number of times on a diminishing length of thread, including: a driving member having periods of activity of constant duration, a driven take-up member having intermittent periods of activity of diminishing duration, and a driving connection, between the two members, to drive the driven member in one direction only and 10 only during the latter's diminishing periods of activity, first during a slack take-up period the duration of which is controlled by the length of the thread, and then, in response to resistance of the thread, during a stitch-tensioning period of uniform duration regardless of the length of the 15 thread.

6. In a sewing machine, a thread take-up device, to act a number of times on a diminishing length of thread, including: a driving member, a clutch to impart intermittent rotations each of a single revolution to said driving member, a driven take-up member having intermittent periods of activity of diminishing duration, and a driving connection, between the two members, to drive the driven member, during the latter's diminishing periods of activity, first during a slack take-up period the duration of which 25 is controlled by the length of the thread, and then, in response to resistance of the thread, during a stitch-tensioning period of uniform duration regardless of the length of the 30 thread.

40 7. In a sewing machine, a thread take-up device, to act a number of times on a diminishing length of thread, including: a driving member having periods of activity of constant duration, an oscillatory driven take-up member having intermittent periods of activity of diminishing duration, and a driving connection, between the two members, to drive the driven member in one direction only and only during the latter's 45 diminishing periods of activity, first during a slack take-up period the duration of which is controlled by the length of the thread, and then, in response to resistance of the thread, during a stitch-tensioning period of uniform duration regardless of the length of the 50 thread.

8. In a sewing machine, a thread take-up device, to act a number of times on a diminishing length of thread, including: a driving member, a clutch to impart intermittent rotations each of a single revolution to said driving member, an oscillatory driven take-up member having intermittent periods 55 of activity of diminishing duration, and a

driving connection, between the two members, to drive the driven member in one direction, during the latter's diminishing periods of activity, first during a slack take-up period the duration of which is controlled by the length of the thread, and then, in response to resistance of the thread, during a stitch-tensioning period of uniform duration regardless of the length of the 70 thread.

9. In a sewing machine, a thread take-up device, to act a number of times on a diminishing length of thread, including: a rotatable driving member having periods of activity of constant duration, a driven rotatable take-up member having intermittent periods of activity of diminishing duration, and a driving connection, between the two members, to drive the driven member in one direction only and only during the latter's diminishing periods of activity, first during a slack take-up period the duration of which is controlled by the length of the thread, and then, in response to resistance of the thread, during a stitch-tensioning 80 period of uniform duration regardless of the length of the thread.

10. In a sewing machine, a thread take-up device, to act a number of times on a diminishing length of thread, including: a driving member having periods of activity of constant duration, a driven take-up member having intermittent periods of activity of diminishing duration, and a driving connection, between the two members, to drive the driven member in one direction only and only during the latter's diminishing periods of activity, first during a slack take-up period the duration of which is controlled by the length of the thread, and then, in response to resistance of the thread, during a stitch-tensioning 90 period of uniform duration regardless of the length of the thread.

11. In a sewing machine, a thread take-up device, to act a number of times on a diminishing length of thread, including: a

115 rotatable driving member having periods of activity of constant duration, a driven rotatable take-up member having intermittent periods of activity of diminishing duration, a driving connection, between the two members, to drive the driven members in one direction only and only during the latter's diminishing periods of activity, first during a slack take-up period the duration of which is controlled by the length of the thread, and then, in response to resistance of the thread, during a stitch-tensioning period of uniform duration regardless of the length of the thread, and means, independent of said connection, to restore in the other direction the driven member to its original position after each stitch-tensioning period.

120 12. In a sewing machine, a thread take-up device, to act a number of times on a diminishing length of thread, including: a rotatable driving member having periods of activity of constant duration, a driven rotatable take-up member having intermittent periods of activity of diminishing duration, a driving connection, between the two members, to drive the driven members in one direction only and only during the latter's diminishing periods of activity, first during a slack take-up period the duration of which is controlled by the length of the thread, and then, in response to resistance of the thread, during a stitch-tensioning period of uniform duration regardless of the length of the thread, and means, independent of said connection, to restore in the other direction the driven member to its original position after each stitch-tensioning period.

rection the driven member to its original position after each stitch-tensioning period.

12. A take-up device including: a rotating driving cam, a rotatable driven member, 5 a thread-engaging arm movably supported on the driven member and releasably engaged by the cam, and a spring device on the driven member to prevent disengagement of the cam and arm until the resistance offered by the thread admits of movement of the arm over the cam surface.

13. A take-up device including: a rotating driving cam, a rotatable driven member, 15 a thread-engaging arm pivotally supported on the driven member and releasably engaged by the cam, and a spring device on the driven member to prevent disengagement of the cam and arm until the resistance offered by the thread admits of movement of the arm over the cam surface.

14. A take-up device including: an intermittently rotating driving cam, an oscillatory driven member, moved in one direction by the cam, a thread-engaging arm mov- 25 ably supported on the driven member and releasably engaged by the cam, and a spring device on the driven member to prevent disengagement of the cam and arm until the resistance offered by the thread admits of movement of the arm over the cam surface.

15. A take-up device including: an intermittently rotating driving cam, an oscillatory driven member moved in one direction by the cam, a thread-engaging arm pivotally 35 supported on the driven member and releasably engaged by the cam, and a spring device on the driven member to prevent disengagement of the cam and arm until the resistance offered by the thread admits of movement of the arm over the cam surface.

16. A take-up device including: an intermittently rotating driving cam, an oscillatory driven member moved in one direction by the cam, a thread-engaging arm movably 45 supported on the driven member and releasably engaged by the cam, a spring device on the driven member to prevent disengagement of the cam and arm until the resistance offered by the thread admits of movement of the arm over the cam surface, a finger carried by the arm, and orbit-directing means to cause the finger to travel in a certain orbit during the movement of the oscillatory member in one direction and in

55 another orbit during the movement of the oscillatory member in the other direction.

17. A take-up device including: an intermittently rotating driving cam, an oscillatory driven member moved in one direction by the cam, a thread-engaging arm pivotally supported on the driven member and releasably engaged by the cam, a spring device on the driven member to prevent disengagement of the cam and arm until the 65 resistance offered by the thread admits of

movement of the arm over the cam surface, a finger carried by the arm, and orbit-directing means to cause the finger to travel in a certain orbit during the movement of the oscillatory member in one direction and in another orbit during the movement of the oscillatory member in the other direction. 70

18. A take-up device including: a rotating driving cam, a rotatable driven member, a thread-engaging arm movably supported on the driven member and releasably engaged by the cam, a spring device on the driven member to prevent disengagement of the cam and arm until the resistance offered by the thread admits of movement of the arm over the cam surface, and a thread-engaging finger slidably carried by the arm. 75

19. A take-up device including: a rotating driving cam, a rotatable driven member, a thread-engaging arm pivotally supported on the driven member and releasably engaged by the cam, a spring device on the driven member to prevent disengagement of the cam and arm until the resistance offered by the thread admits of movement of the arm over the cam surface, and a thread-engaging finger slidably carried by the arm. 80

20. A take-up device including: an intermittently rotating driving cam, an oscillatory driven member moved in one direction by the cam, a thread-engaging arm movably supported on the driven member and releasably engaged by the cam, a spring device on the driven member to prevent disengagement of the cam and arm until the resistance offered by the thread admits of movement of the arm over the cam surface, a thread-engaging finger slidably carried by the arm, and means to cause such sliding movement of the finger that it describes a different orbit when the oscillatory member is driven by the cam from that it describes when the oscillatory member returns. 90

21. A take-up device including: an intermittently rotating driving cam, an oscillatory driven member moved in one direction by the cam, a thread-engaging arm pivotally supported on the driven member and releasably engaged by the cam, a spring device on the driven member to prevent disengagement of the cam and arm until the resistance offered by the thread admits of movement of the arm over the cam surface, a thread-engaging finger slidably carried by the arm, and means to cause such sliding movement of the finger that it describes a different orbit when the oscillatory member is driven by the cam from that it describes when the oscillatory member returns. 100

22. A take-up device including: a rotatable member, an arm supported on the rotatable member, and a thread-engaging finger slidable in a rectilinear path, carried by the arm. 110

23. A take-up device including: a rotata- 125

ble member, an arm supported on the rotatable member, a thread-engaging finger, slidably in a rectilinear path, carried by the arm, and means to cause sliding movement 5 of said finger with respect to said arm.

24. A take-up device including: a rotatable member, an arm supported on the rotatable member, a thread-engaging finger slidably carried by the arm, a cam to cause 10 sliding movement of said finger with respect to said arm, and means to shift the position of the cam back and forth to vary the orbit of the finger.

25. A take-up device including: an oscillatory member, an arm supported on said member, and a thread-engaging finger slidably in a rectilinear path, carried by the arm.

26. A take-up device including: an oscillatory member, an arm supported on said member, a thread-engaging finger, slidably in a rectilinear path, carried by the arm, and means to cause sliding movement of said finger with respect to said arm.

27. A take-up device including: an oscillatory member, an arm supported on said member, a thread-engaging finger, slidably in a rectilinear path, carried by the arm, and means to cause such sliding movement 30 of said finger with respect to said arm that the finger describes one orbit during the movement of the member in one direction and a different orbit during the movement of the member in the other direction.

28. A take-up device including: an oscillatory member, an arm supported on said member, a thread-engaging finger slidably carried by the arm, and a cam mounted independently of the oscillatory member to cause such sliding movement of said finger 40 with respect to said arm that the finger describes one orbit during the movement of the member in one direction and a different orbit during the movement of the finger in the other direction.

29. A take-up device including: an oscillatory member, an arm supported on said member, a thread-engaging finger slidably carried by the arm and means to engage the 50 arm to thereby move the oscillatory member in one direction, said member being moved in the other direction by the thread engaging the finger.

30. A take-up device including: an oscillatory member, an arm supported on said member, a thread-engaging finger slidably carried by the arm, means to cause sliding movement of said finger with respect to said arm, and means to engage the arm to thereby move the oscillatory member in one 60 direction, said member being moved in the other direction by the thread engaging the finger.

31. A take-up device including: an oscillatory member, an arm supported on said

member, a thread-engaging finger slidably carried by the arm, means to cause such sliding movement of said finger with respect to said arm that the finger describes one orbit during the movement of the member in one direction and a different orbit during the movement of the member in the other direction, and means to engage the arm to thereby move the oscillatory member in one direction, said member being moved in the other direction by the thread engaging the finger. 70

32. A take-up device including: an oscillatory member, an arm supported on said member, a thread-engaging finger slidably carried by the arm, a cam mounted independently of the oscillatory member to cause such sliding movement of said finger with respect to said arm that the finger describes one orbit during the movement of the member in one direction and a different orbit during the movement of the finger in the other direction, and means to engage the arm to thereby move the oscillatory member in one direction, said member being moved in the other direction by the thread engaging the finger. 75

33. The combination with two oscillatory take-up devices acting in alternation, of means for driving said devices positively 80 in one direction, each device returning the other one in the other direction, of brake mechanism for each device active when the device is driven positively and inactive when the device is returning. 85

34. A take-up device including: an arm rotatably mounted, and a thread-engaging finger, slidably in a rectilinear path, carried by the arm.

35. A take-up device including: an arm rotatably mounted, a thread-engaging finger slidably carried by the arm, an actuating member to cause sliding movement of said finger with respect to said arm, and means to vary the effect of the actuating member 105 to vary the orbit of the finger. 110

36. A take-up device including: an arm mounted to oscillate, and a thread-engaging finger, slidably in a rectilinear path, carried by the arm. 115

37. A take-up device including: an arm mounted to oscillate, a thread-engaging finger, slidably in a rectilinear path, carried by the arm, and means to cause such sliding movement of said finger with respect to said arm that the finger describes one orbit during the movement of the arm in one direction and a different orbit during the movement of the arm in the other direction. 120

38. In a sewing machine, a needle chuck, an oscillatory member to open and close said chuck, two wings on said oscillatory member at opposite sides thereof, and rotating members to alternately actuate the 125 130

chuck through the intermediary of the wings.

39. In a sewing machine, a needle chuck, an oscillatory member to open and close said chuck, two wings on said oscillatory member at opposite sides thereof, two rocking members to alternately engage the wings, and two rotating members to alternately rock the rocking members.

10 Signed at Amsterdam, in the county of Montgomery, and State of New York, this 12th day of December, 1928.

FRANK J. KAUFMANN.
